SHEET APPLYING DEVICE

Ernest Hope, Leicester, England, assignor to
 United Shoe Machinery Corporation, Borough
 of Flemington, N. J., a corporation of New
 Jersey

Application May 6, 1939, Serial No. 272,171
 In Great Britain June 7, 1938

8 Claims. (Cl. 51—275)

This invention relates to improvements in sheet applying devices for abrading tools and is herein disclosed as embodied in a device for pressing sheets of abrading material against the abrasive carrying surface of discoidal tools.

It is an object of the present invention to facilitate the application of abrasive disks to such abrading tools and to insure that the disks will be properly located on the tool and will be firmly attached thereto. In accordance with this object the illustrated device comprises an annular tool supporting member, a pressing plate, a lever arranged to force the plate against the abrasive carrying surface of the tool and means for centering the tool with relation to the pressing plate.

The invention will be better understood when considered with relation to the accompanying drawing, in which the figure is an elevation, partly in section, of the disk applying device with a tool inserted therein.

The invention is illustrated as employed in applying an abrasive sheet to a rotary abrading tool having a hollow stem 10 which is internally tapered and is adapted to be fitted upon and rotated by a downwardly projecting tapered spindle that commonly forms a part of a well-known type of shoe bottom finishing machine. One end of the stem carries a flange 12 against which a rubber backing disk 14 is held by a screw 16. An abrasive sheet 18, which may conveniently be formed in the shape of an annular disk, is cemented, preferably by means of a permanently tacky adhesive, to the lower or abrasive carrying surface of the rubber disk 14.

The abrasive sheet 18 is slightly larger in diameter than the disk 14 so that in use it tends to roll over the edge of the disk, thus insuring the disk will not come in contact with the work. Tools of this type are frequently used to scour those portions of the soles of shoes which are adjacent to the heel breast, since the flexibility of the rubber backing disk 14 permits the tool to conform to the contours of the sole.

In order to provide for accurate positioning and firm attachment of the abrasive ring-shaped disk 18 to the tool, an applying device is provided having a stem 20 which may be readily grasped by the operator and used as a handle. Projecting upwardly from the stem are two arms 22 spaced in the manner of a fork and carrying a C-shaped tool supporting member 24 pivoted on coaxial pins 26 extending inwardly from the arms 22. An opening 27 in one side of the tool supporting member is large enough to enable the stem 10 of the tool to pass through it, thus per-

mitting the sheet applying device to be used without removing the tool from the machine.

The stem 20 is drilled to receive a tube 28 which is slidable therein. The end of the tube 28 adjacent to the arms 22 carries a circular pressing plate 30 from the center of which projects a pin 32. The plate 30, the tube 28 and the pin 32 are fastened together by means of a pin 34.

A lever 36 is fulcrumed at 38 on the stem and has a short arm 40 which is arranged to extend through a slot 42 in the tube 28 and engage a cross pin 44 fixed in the tube. A screw 46 engaging the slot 42 prevents the tube from rotating.

To use the device to apply a disk to the tool the operator slips the device over the tool, passing the stem 10 through the opening 27 in the tool supporting member and seats the tool on the supporting member, with the upper surface of the rubber disk 14, i. e., the back of the tool resting against the lower surface of the supporting member 24. The operator then places an annular disk of abrasive material on the presser plate 30 with its adhesive side up. He then raises the presser plate 30 with his thumb until the pin 32 enters an aperture 48 in the center of the screw 16, thus centering the tool with relation to the presser plate and insuring that the overhang of the abrasive disk 18 will be equal at all points about the circumference of the rubber bearing disk 14.

During this operation the tube 28 slides upwardly in the stem 20 sufficiently to permit the arm 40 to enter the slot 42 and engage the cross-pin 44. The operator then applies pressure to the lever 36 to raise the presser plate until the adhesive-coated abrasive ring is brought into engagement with the working face of the rubber disk 14, whereupon the abrasive ring and the rubber backing disk are clamped between the presser plate 30 and the tool supporting member 22, thus insuring a firm adhesion at all points between the abrasive disk and the rubber bearing disk 14. It is to be noted that the tool support is enabled, by reason of the pivotal mounting on the pins 26, to tilt to compensate for variations in the thickness of the abrasive disk or of the tool, and thus insures equal pressure at either side of the tool.

The extent of the pin 32 projecting above the presser plate 30 insures that the pin will engage the tool and center it with relation to the presser plate before any contact can be made between the abrasive disk and the rubber bearing disk 14.

Having thus described the invention, what is

claimed as new and desired to secure by Letters Patent of the United States is:

- 5 1. A device for applying abrasive disks to rotary abrading tools comprising a frame, a pair of pivot members carried by said frame, an annular tool supporting member mounted on said pivot members for tilting movement in said frame, and means cooperating with said supporting member to press an abrasive disk against the 10 working face of the tool to attach the abrasive disk adhesively to the tool.
- 15 2. A device for applying abrasive disks to rotary abrading tools comprising a frame, pivot members carried by said frame, an annular tool supporting member mounted for rocking movement on said pivot members and having an opening in its side, and means for pressing an adhesive-coated abrasive disk against the working face of the tool to attach the abrasive disk 20 to the tool.
- 25 3. A device for applying abrasive disks to rotary abrading tools comprising an annular support constructed and arranged for engagement with the back of a disk-shaped abrading tool, a frame on which said support is mounted, a circular plate mounted in said frame for movement toward the working face of a tool engaging said support, means for urging said plate toward the tool to cause an adhesive-coated abrasive disk 30 carried by the plate to adhere to the working face of the tool, and a pivotal connection between said annular support and said frame to enable the support to tilt and thereby insure uniform pressure between the circular plate and 35 the tool.
- 40 4. A device for applying abrasive disks to rotary abrading tools comprising a frame, a C-shaped tool supporting member tiltably mounted in said frame, a presser plate, and a lever for urging said plate toward the working face of a tool held by said support to apply by pressure to the working face of the tool an adhesive-coated disk.
- 45 5. A device for applying an abrasive disk to a rotary abrading tool on a shaft, said device comprising a C-shaped support constructed and arranged to be slipped over the stem of a disk-shaped abrading tool and to engage the back

thereof, a frame on which said support is mounted, a circular plate mounted in said frame for movement toward the working face of a tool engaging said support, means for urging said plate toward the tool to cause an adhesive-coated abrasive disk carried by the plate to adhere to the working face of the tool, and an axial projection on said plate engageable with an axial recess in the tool to center the tool.

6. A device for applying abrasive disks to rotary abrading tools comprising a support for the back of a disk-shaped abrading tool, said support being in the form of an annulus having an opening to enable the stem of the abrading tool to enter the annulus, a frame, pivot members carried by said frame, said support being mounted for tilting movement on said pivot members, a circular plate mounted in said frame for movement toward the working face of the tool, and means for urging said plate toward the tool to cause an adhesive-coated abrasive disk carried by the plate to adhere to the working face of the tool.

7. A device for applying an abrasive disk to a rotary abrading tool on a shaft, said device comprising a frame, a C-shaped tool supporting member constructed and arranged to be slipped over the stem of the tool and to engage the back thereof, a presser plate slidably mounted in said frame for movement toward and from said support, and a lever for applying pressure to force said plate toward the working face of a tool held in said support to adhesively attach an abrasive disk to said tool.

8. A device for applying abrasive disks to rotary abrading tools comprising a frame, an annular tool supporting member tiltably mounted on said frame and having an opening in one side thereof to admit the spindle of a tool, a presser plate slidably mounted in said frame for movement toward and from said support, a lever for applying pressure to force said plate toward the working face of a tool held in said support to press an adhesive-coated abrasive disk against the working surface of the tool, and a pin engageable with a recess in the tool for centering said tool with relation to said presser plate.

ERNEST HOPE.
